UNITED STATES PATENT OFFICE.

CHARLES A. XARDELL, OF UTICA, NEW YORK.

HEATER.

1,353,556.

Specification of Letters Patent. Patented Sept. 21, 1920.

Application filed July 11, 1917. Serial No. 179,790.

To all whom it may concern:

Be it known that I, CHARLES A. XARDELL, a citizen of the United States, residing at Utica, in the county of Oneida and State of 5 New York, have invented or discovered certain new and useful Improvements in Heaters, of which the following is a specification, reference being had therein to the accompanying drawing.

10 This invention relates to heaters or furnaces for heating systems of the type employing a circulating fluid as a medium for distributing the heat generated by the furnace, and has for its object to increase the 15 rate or speed of flow of the circulating fluid, thereby increasing the effective volume of said fluid and reducing the losses by radiation between the point of generation and the desired points of application of the heat, 20 and, at the same time, to provide for a quick and efficient heating of the fluid by causing all of said fluid, as it circulates, to be brought into as close proximity as possible to the 25 source of heat, said fluid passing the region of maximum heat in minimum volume.

The foregoing and other objects of the invention, together with means whereby the same may be carried into effect, will best be understood from the following description 30 of certain forms or embodiments thereof illustrated in the accompanying drawing. It will be understood, however, that the particular constructions described and shown have been chosen for illustrative purposes merely, and that the invention, as defined by the claims hereunto appended, may be otherwise practised without departing from the spirit and scope thereof.

In said drawing—

40 Figure 1 is a vertical sectional view of a hot air furnace constructed in accordance with the invention.

Fig. 2 is a similar view illustrating the invention embodied in a hot water heater.

45 Referring first to Fig. 1 the furnace proper may be of any usual or well known construction and as shown comprises a casing 15 inclosing an ash pit and a second casing 16 inclosing a combustion chamber

50 communicating at its top through a drum 17 with the flue or chimney. Surrounding the furnace proper, and immediately adjacent thereto, is an air chamber or conduit comprising a casing 18 secured at its lower 55 edge to a base plate 19 upon which the fur-

nace is supported, and at its upper edge to a ring or annulus 20 constituting the lower edge of a distributing chamber 21 with which communicate delivery pipes 22. Said air chamber is provided at its bottom with 60 one or more air inlets 23 through the base plate 19, and at its upper end with an air outlet 24 through the annulus 20, while the casing 18 provides an unbroken wall extending from the inlet or inlets to the outlet. Said wall or casing 18 is not equally spaced throughout its length or height from the wall or casing of the furnace, but, from the bottom, converges toward the furnace 65 wall to a level adjacent the zone of greatest 70 heat of the combustion chamber (that is to say, to a level somewhat above the furnace grate), and thereafter diverges therefrom, so that the horizontal cross sectional area of the air conduit diminishes from the bottom thereof to the zone of maximum heat, 75 is smallest at that point, and thereafter increases.

As a result of this construction and arrangement the velocity of flow of the air 80 moving upwardly through its conduit is accelerated as the constricted portion of said conduit is approached, becoming greatest at the zone of maximum heat where the heating effect is greatest, said heating effect being augmented by reason of the fact that the air passes the region of maximum heat in 85 minimum volume, being spread out in a relatively thin layer or sheet immediately adjacent the furnace wall. 90

As shown in Fig. 1 there is provided a cylindrical outer wall or casing 25 secured at its upper and lower edges respectively to the annulus 20 and base plate 19 adjacent the edges of the wall or casing 18, said casing 25 surrounding said casing 18. By reason of the cylindrical shape of the casing 25 and the reduced diameter of the casing 18 at a point intermediate its ends, giving the same a substantially double frusto-conical form, said casings inclose between them a dead air space which serves as a heat insulator for the air heating chamber or conduit. 100

In the construction shown in Fig. 2, 26 105 denotes the ash pit, 27 the furnace grate, and 28 the wall or casing of the combustion chamber, which combustion chamber communicates at its top with the flue 29. Surrounding the combustion chamber is a water 110

chamber or conduit formed by a wall or casing 30 so spaced from the wall 28 that the horizontal cross sectional area of said water chamber or conduit is smallest adjacent the zone of greatest heat, and greater both above and below said zone, as in the form of the invention first described. To this end, in the construction shown, the wall or casing 30 is of a double frusto-conical form similar to that of the wall or casing 18. The water chamber is provided adjacent its bottom with one or more inlets, with which the return pipes 31 of the system communicate, and at its top with one or more outlets 32 which communicate with a distributing chamber 33 from which lead the risers or delivery pipes 34.

Water moving upwardly through the water chamber or conduit is accelerated in its flow as it passes upwardly through the constricted portion of said conduit, the action being similar to that of the well known Venturi tube, said water being brought, in minimum volume, into close proximity to the combustion chamber at its zone of maximum heat, so that said water quickly absorbs the requisite amount of heat. The relatively great amount of heat in proportion to the volume of water at this point produces a tendency to ebullition or formation of steam, in small quantities, at the constricted portion. This steam, rising in the water chamber, together with the expansion of the water due to its heating, imparts an upward impulse to the heated water in the risers, consequently resulting in a quick return of water from the circulation system to the heater.

It will thus be seen, that, in both forms of the invention shown and described, the velocity of the circulating fluid (air or water) is accelerated, beyond that normally caused by heat in the usual heating system, by being caused to pass through a conduit of restricted cross sectional area, that said fluid is quickly and efficiently heated by being brought in relatively small volume into close proximity to a source of a relatively great amount of heat, and that the construction is such that the heating of the fluid is caused to counteract tendency to retardation caused by subsequently increasing cross sectional area of the conduit; thereby resulting in the rapid circulation of a highly heated fluid, increasing the effective volume of the latter, and reducing the losses due to improper radiation and the amount of fuel

required for a given useful radiation at the desired points of application.

Having thus described my invention, I claim:

1. In a furnace or heater, the combination with a combustion chamber, of a distributing chamber, a fluid chamber or conduit freely opening into said distributing chamber, said fluid chamber or conduit surrounding said combustion chamber and having an inlet at its bottom, an outlet at its top, and unbroken walls extending from said inlet to said outlet, said conduit tapering upward from its bottom to a point adjacent the zone of greatest heat of said combustion chamber, and thereafter increasing in diameter upward to said outlet, thus forming an unobstructed Venturi tube around said combustion chamber. 65 70 75

2. A furnace or heater having a combustion chamber formed by an unbroken wall or casing, and a second unbroken wall or casing surrounding said first-named wall or casing outside of the combustion chamber casing and thus affording, between said walls or casings, a fluid chamber or conduit which converges upwardly from its bottom and then flares outwardly upward, to form 80 85 an unobstructed Venturi tube conduit, around the combustion chamber, for the fluid, said walls or casings most closely approaching each other at a point adjacent the zone of maximum heat of said combustion chamber, and a distributing chamber 90 into which said fluid chamber or conduit opens.

3. A furnace or heater having a combustion chamber formed by an unbroken wall 95 or casing, a second unbroken wall or casing outside of the combustion chamber casing and thus affording, between said walls or casings, a fluid chamber or conduit which converges outwardly upward, to form an 100 unobstructed Venturi tube conduit, around the combustion chamber, for the fluid, said walls or casing most closely approaching each other at a point adjacent the zone of maximum heat of said combustion chamber, 105 and a third wall or casing surrounding said second wall or casing and secured thereto at its ends, said second and third walls or casings inclosing between them a dead air space, and a distributing chamber into 110 which said fluid chamber or conduit opens.

In testimony whereof I affix my signature.

CHARLES A. XARDELL.
